FRANK B. BRADLEY, OF CHICAGO, ILLINOIS, ASSIGNOR TO AJAX FORGE COMPANY, A CORPORATION OF DELAWARE.

INSULATED SWITCH-ROD.

1,191,149.

Application filed March 2, 1915. Serial No. 11,588.

Patented July 18, 1916.

To all whom it may concern:

Be it known that I, FRANK B. BRADLEY, a citizen of the United States, residing at Chicago, in the county of Cook and State of Illinois, have invented certain new and useful Improvements in Insulated Switch-Rods; of which the following is a specification.

This invention relates to switch rods, and more particularly to an improved insulated switch rod adapted for use in connection with the switch point rails of a railway track.

It is now common practice to employ switch rods having reach bars formed in sections which are secured together and insulated from each other between the rails of the track by butt or lap-insulating joints, in order to break the electric circuit which would otherwise be formed between the rails of the track, and which would interfere with the operation of electrical signal systems in which the rails are employed as portions of the signal circuits.

The principal object of my invention is to provide an integral switch rod reach bar in combination with means for preventing the formation of an electric circuit between the rails of the track through the switch rod.

A further object is to provide a switch rod having a single unbroken reach bar extending continuously between the rails of the track, in combination with means for insulating said rod from the rail at one side of the track. I provide an integral switch rod reach bar which extends between the rails of the track, being secured to the switch or point rails and extending beneath the continuous traffic rails, and I further provide means for preventing an electric circuit through the rod between the continuous rail, or the switch rail, at one side of the track and the continuous rail, or the switch rail, at the other side of the track.

A further object of the invention is to provide an integral reach bar with adjustable means for securing the same to the switch point rails, whereby the point rails may be adjusted relatively to said bar, in combination with means for insulating said adjustable securing means from said rod.

These and other objects of my invention will be more particularly set forth in the following specification, taken in connection with the accompanying drawings, in which

I have illustrated a specific embodiment of my invention.

In the drawings: Figure 1 is a plan view of a portion of a switch with my invention applied thereto, the switch rod being embodied in the form of a head rod, as used at the point of the switch. Fig. 2 is a sectional view, taken on the line 2—2 of Fig. 1; Fig. 3 is a view similar to Fig. 2, showing my invention embodied in a spread rod, as employed some distance from the point of the switch; Fig. 4 is an enlarged sectional view, taken on the line 4—4 of Fig. 1, showing the details of the insulating joints and adjustable connections. Fig. 5 is an enlarged top plan view of the structure shown in Fig. 4 with the rails removed; Fig. 6 shows perspective views of the insulating elements employed in insulating the switch rod from the point rail; and Fig. 7 shows perspective views of insulating elements employed in insulating the switch rod from the continuous traffic rail.

In Fig. 1 of the drawings I have shown an ordinary form of point switch, including the two continuous fixed traffic rails 10 and 11, and the movable rails 12 and 13, all supported upon the ties 14. Each point rail, as usual, is secured to a grip or chair A, which, in turn, is secured to the reach bar of the switch rod 15 by intermediate means, of a form adapted for adjusting the point rail relatively to the switch rod. The intermediate means which I have illustrated is, in part, more particularly shown and described in my copending application Serial No. 874,436, filed November 28, 1914. The intermediate connecting means will be described in connection with one point rail only.

As shown in all of the figures of the drawings, except Fig. 3, the switch rod is embodied in the form of a head rod, as used at the point of the switch, and it comprises a single integral reach bar which extends continuously between the rails of the track and beneath the continuous rails 10 and 11, being apertured at its extremities for attachment to the switch-operating mechanism.

The grip or chair A is provided with a flange 16, which is attached to the point rail by bolts 17, or other suitable means; and the intermediate means by which said grip is secured to the reach bar comprises

a bar or base plate B, which is secured to said bar in the manner hereinafter to be described. Formed upon or rigid with the bar B is an upwardly extending stud 18, which 5 is adapted to project through a relatively larger circular opening or aperture 19 formed in the horizontally extending base member 20 of the grip A. The intermediate space between the stud 18 and the walls of 10 the aperture 19 is adapted to be occupied by part of the adjustment member C. The upwardly projecting stud 18 has a non-circular periphery, which is here shown as corrugated or fluted, and the downwardly extending circular part 21 of the adjustment member is provided with a socket 22, which 15 is of the same size and form as the upwardly extending stud, the outer walls of said socket being corrugated in the same 20 manner as said stud. The circular part 21 of the adjustment member is adapted to fit the circular aperture 19 in the grip A, and the adjustment member C is further provided with a downwardly projecting flange 25 23, between which and the circular part there is an annular channel 24, designed to fit over an upwardly projecting lip 25, which surrounds the opening 19 in the grip. The socket 22 is eccentrically located with 30 respect to the periphery of the circular part 21 of the adjustment member, and said member is provided with a bolt hole 26, which is centrally located with respect to said socket. A continuation 27 of this bolt hole 35 extends centrally through the stud 18 and through the plate B in alinement with a bolt hole 28 in the reach bar. A bolt 29, passed through these bolt holes and its upper threaded extremity, engages a nut 30, 40 which seats upon the adjustment member C and is retained in adjusted position by a pin 31. The grip A has a projecting lug 33 which normally underlies a hook projection 34 on the plate B, thereby normally preventing 45 substantial vertical displacement of the grip and reach bar when the nut is withdrawn. It will be seen that forces are transmitted between the grip and reach bar through the adjustment member and stud 50 18, thus relieving stress upon the bolt.

In assemblage the grip A, to which the switch point is attached, is placed in position with the opening 19 therein surrounding the stud 18, and the adjustment member 55 C is then placed in position, as shown particularly in Fig. 4, with its projection 21 fitting within the opening 19, and its socket 22 fitting around the stud 18. By reason of the eccentric location of the socket with respect to the outer circular periphery of the part 21, an adjustment of the position of the switch point rail relatively to the body 60 of the switch rod, and relatively to the fixed rail, can be obtained by changing the member C to different angular positions, eight of

said different angular positions being possible with the corrugated stud and socket illustrated. Eight adjustments are possible by reason of the fact that the corrugations on the stud 18 are not symmetrically disposed with reference to the axis 32—32 of the switch rod, as shown particularly in Fig. 5, and likewise the corrugations around the walls of the socket 22 of the adjustment member C are not symmetrically arranged 75 with reference to a line joining the center of the projection 21 with the center of the socket.

The base plate seats upon a sheet 35 of insulating fiber, or other insulating material, which serves to insulate said plate from the reach bar 15, and said plate is secured to the reach bar by means of rivets 36, which pass through the apertures in the base plate and through continuations 37, of 80 these apertures which are formed in the sheet of insulating fiber in alinement with the apertures 38 in the reach bar. The rivets 36 are insulated from the reach bar by means of bushings 39, of insulating material, 90 which surround said rivets in the apertures 38 and, preferably, extend upwardly through the apertures 37 in the sheet of insulating fiber. The bushings also extend downwardly through the washers 40, of insulating material, which surround the rivets below the reach bar, and which serve to insulate the metallic washers 41 from the reach bar. These metallic washers seat upon the upset heads 36^a of the washers 36, and it will be 100 apparent that by means of the construction just described the rivets are effectively insulated from the reach bar. The sheet of insulating fiber 35 is also provided with an aperture 42 in alinement with the bolt holes 105 27 and 28 in the plate B and reach bar, respectively, and the bolt 29 is insulated from the reach bar by means of a bushing 43 of insulating material which surrounds said bolt within the bolt hole 28. This bushing 110 extends downwardly through a washer 44, of insulating material, which serves to insulate the metallic washer 45 from the reach bar. This metallic washer seats upon the head 29^a of the bolt 29, and thus it will be 115 apparent that all of the parts of the base plate and the elements carried thereby, as well as the connections between those parts and the reach bar, are all effectively insulated from the reach bar.

The reach bar of the switch rod is offset 120 downwardly at 15^a, and extends outwardly beneath the fixed traffic rail to form a connection with the switch-operating mechanism, as above described. In order to insulate the switch rod from the fixed traffic rail, I provide a sheet 50 of insulating fiber, or other insulating material, which is located on the switch rod adjacent the fixed traffic rail, and upon this sheet of insulating fiber 130

is seated a metallic wearing plate 51, the upper surface of which is countersunk at 52 to receive the heads of the rivets 53, by means of which said wearing plate and sheet 5 of insulating fiber are secured to the switch rod. The rivets 53 are insulated from the switch rod by bushings 54, of insulating material, and these bushings are extended downwardly through the washers 55, also 10 of insulating material, which serve to insulate the metallic washers 56 and the upset heads 53^a of said washers from the switch rod. As the switch rod is manipulated to throw the switch rails into engagement with 15 the fixed traffic rails, the wearing plate 51 will take up any wear which may occur by reason of the contact thereof with the under side of the adjacent fixed rail, and at the same time the sheet of insulating fiber 50 20 will prevent the formation of an electric circuit between the adjacent fixed rail, through the switch rod, to the fixed rail or point rail at the other side of the track.

The base plate B and the adjustable connections, by means of which the switch rod is secured to the point rail 12 at the other side of the track, are the same as those above described; and it will therefore be understood that either of the point rails 12 and 13 may 25 be adjusted relatively to the switch rod and to the adjacent fixed rails. I prefer, however, to connect one of the members B—by means of which the connection is formed between the switch rod and point rail—directly to the reach bar without the use of insulating means, inasmuch as the insulating means employed to insulate the other switch point rail from the switch rod will serve to prevent the formation of an electric circuit 30 through the switch rod from the last mentioned point rail to either the point rail or the fixed rail at the other side of the track. For a similar reason I prefer to employ only one of the wearing plates 51, and insulating sheets 50, since the use of these elements at one side of the track, as described, will prevent the formation of an electric circuit between the adjacent fixed rail and either the point or fixed rails at the other 35 side of the track. It will be understood, however, that the insulating elements may be used at both sides of the track, if desired.

In Fig. 3 I have illustrated my invention as embodied in a head rod 60, such as is employed some distance from the point of the switch to connect the point rails for a parallelogram movement. In this instance, one of the base plates B' is directly connected to the switch rod 60, while the other base plate B' is insulated therefrom in the manner above described.

From the foregoing description, it will be evident that I have provided an integral reach bar which extends continuously between the rails of the usual track, and that

I have provided, in combination therewith, effective means for breaking the electric circuit between the rails, thereby simplifying the construction of the switch rod and increasing the durability and efficiency thereof in operation. 70

While I have shown and described a particular form of my invention, and have explained the operation thereof in a particular manner, it will be understood that I contemplate changes in form and arrangement of parts, as circumstances may suggest or necessity render expedient, without departing from the scope of the invention as defined in the appended claims. 75

I claim:—

1. In a device of the class described, an integral reach bar extending continuously between and beneath the fixed rails of a railway track, said reach bar having an upper plane surface, and means seated on said surface and secured to said reach bar for insulating the same from one of said rails. 80

2. In a device of the class described, a switch rod extending beneath a fixed rail of a railway track, said switch rod having an upper plane surface adjacent said rail, and means seated on said surface and secured to said switch rod for insulating the same from 90 said rail. 95

3. In a device of the class described, a switch rod extending adjacent to a rail of a railway track, a plate seated on said rod adjacent said rail, a sheet of insulating material between said plate and said rod, means 100 to secure said plate and said insulating material to said rod, and means to prevent an electric connection between said rail and said rod through said securing means.

4. In a device of the class described, a pair of continuous rails, a pair of point rails, an integral reach bar secured to said point rails and extending beneath said continuous rails, means to insulate said reach bar from one of said point rails, and independent means 110 to insulate said reach bar from one of said continuous rails. 105

5. In a device of the class described, a switch rod extending adjacent to a rail of a railway track, means to insulate said rod 115 from said rail, means to secure said insulating means to said rod, and means to insulate said securing means from said rod.

6. In a device of the class described, an integral reach bar extending continuously 120 between and beneath the fixed rails of a railway track, a sheet of insulating material seated on said bar adjacent one of said rails, a plate seated on said insulating material, means to secure said insulating material and said plate to said bar, and means to insulate said securing means from said bar. 125

7. In a device of the class described, a reach bar, a plate secured to said bar, means to insulate said plate from said bar, and a 130

switch point clip connected to and adjustable relatively to said plate.

8. In a device of the class described, a fixed rail, a point rail, a reach bar extending beneath said fixed rail, adjustable means for securing said point rail to said reach bar, means to insulate said adjustable means from said reach bar, and means independent of said adjustable means to insulate said

10 reach bar from said fixed rail.

9. In a device of the class described, a reach bar, a stud projecting from said bar, means to insulate said stud from said bar, an adjustment member having an eccentric 15 seat adapted to engage said stud, means for preventing rotation of said adjustment member, and a clip engaging said adjustment member.

10. In a device of the class described, a 20 switch rod, a stud projecting from said rod, a clip secured to a point rail and operatively connected to said stud, and means to prevent an electric connection between said switch rod and said rail through said stud 25 and clip.

11. In a device of the class described, a switch rod, a stud projecting from said rod, a clip secured to a point rail and operatively connected to said stud, and means to 30 insulate said stud from said rod.

12. In a device of the class described, a reach bar having a substantially plane upper surface, a plate seated on said surface, means to insulate said plate from said bar,

and a switch point clip operatively connected to said plate.

13. In a device of the class described, a switch rod, a clip adapted to be secured to a rail, a stud projecting from said rod and operatively connected to said clip, whereby 40 stresses are transmitted between said rail and said rod through said stud, and means to insulate said stud from said rod.

14. In a device of the class described, a 45 switch rod, a grip adapted to be secured to a rail, said grip and said rod carrying parts having upwardly extending coacting surfaces through which horizontally acting forces are transmitted from said rail to said rod, means to insulate said rod from said 50 rail, and a bolt to hold said elements in assembled relation.

15. In a device of the class described, a 55 railway rail, a switch rod having a substantially plane upper surface, a plate seated on said surface and secured to said rod, a clip connected to said rail and operatively connected to said plate, and means for preventing an electric connection between said rail and said rod through said clip and said 60 plate.

In testimony whereof, I have subscribed my name.

FRANK B. BRADLEY.
